US00D877215S

(12) **United States Design Patent** (10) Patent No.: **US D877,215 S**
Brandt Sanz et al. (45) Date of Patent: ** Mar. 3, 2020

(54) **MOULD FOR DETERGENT POD**

- (71) Applicant: **The Procter & Gamble Company**,
Cincinnati, OH (US)
- (72) Inventors: **Miguel Brandt Sanz**,
Guldenbunderstraat 13 Tervuren (BE);
Donatella Scafetta, Brussels (BE)
- (73) Assignee: **The Procter & Gamble Company**,
Cincinnati, OH (US)
- (**) Term: **15 Years**
- (21) Appl. No.: **29/646,145**
- (22) Filed: **May 2, 2018**

(30) **Foreign Application Priority Data**

- Nov. 7, 2017 (WO) 5303901
- (51) LOC (12) Cl. **15-09**
- (52) U.S. Cl.
USPC **D15/136**
- (58) **Field of Classification Search**
USPC D15/135, 136; D28/8.1
CPC C11D 17/041; C11D 17/0052
See application file for complete search history.

Darley-Emerson

(57) **CLAIM**

The ornamental design for a mould for detergent pod, as shown and described.

DESCRIPTION

FIG. 1 is a perspective view of a first embodiment of a mould for detergent pod;
FIG. 2 is a front view thereof;
FIG. 3 is a rear view thereof;
FIG. 4 is a left side view thereof;
FIG. 5 is a right side view thereof;
FIG. 6 is a top plan view thereof;
FIG. 7 is a bottom view thereof,
FIG. 8 is a perspective view of a second embodiment of a mould for detergent pod;
FIG. 9 is a front view thereof;
FIG. 10 is a rear view thereof;
FIG. 11 is a left side view thereof;
FIG. 12 is a right side view thereof;
FIG. 13 is a top plan view thereof;
FIG. 14 is a bottom view thereof.
FIG. 15 is a perspective view of a third embodiment of a mould for detergent pod;
FIG. 16 is a front view thereof;
FIG. 17 is a rear view thereof;
FIG. 18 is a left side view thereof;
FIG. 19 is a right side view thereof;
FIG. 20 is a top plan view thereof; and,
FIG. 21 is a bottom view thereof.
